W. H. Johnson

UNITED STATES PATENT OFFICE.

PALMER J. JONES, OF PORT WASHINGTON, NEW YORK.

EDUCATIONAL APPARATUS.

1,392,578.

Specification of Letters Patent.

Patented Oct. 4, 1921.

Application filed May 7, 1920. Serial No. 379,457.

To all whom it may concern:

Be it known that I, PALMER J. JONES, a citizen of the United States of America, residing at Port Washington, New York, have 5 invented a new and useful Educational Apparatus, of which the following is a specification.

My invention relates particularly to apparatus especially useful for classroom instruction, and the main object is to provide simple and inexpensive means by which the teacher may with a minimum of effort and time set up various problems for computation by the pupils.

15 Another object is to enable the teacher to simultaneously display a number of different problems.

Another object is to enable the teacher to readily and quickly change the problems.

20 Another object is to enable the teacher to display various characters for instruction purposes, such for instance, as problems, instructions, commands, and references of various kinds.

25 In the simple form of invention illustrated in the accompanying drawings, I provide a frame in which is mounted a plurality of horizontally disposed sets of display members, one above the other, each of which 30 is preferably longitudinally slidable so that the relative position of the figures thereon may be altered. Each is also preferably reversible so as to make a larger number of combinations possible. Each may also be 35 removable if desired. I also prefer to provide a plurality of vertical shields adapted to be mounted in front of the horizontal display members to cover up portions thereof. These shields are preferably horizontally 40 adjustable and preferably a plurality of them are mounted on a slide so that they may be simultaneously moved across the faces of the display members. In this way it is possible to alter the visible portions 45 of the display members and thus change the displayed problems. I also prefer to provide means for definitely locating the display members so as to maintain uniformity in the columnar arrangement. Other details will be understood from the following 50 specification.

Figure 1 is a front view of apparatus embodying the improvements of my invention.

55 Fig. 2 is an end view and partial vertical section of the same.

Fig. 3 is a detail end view of one of the display members with a guard on one face of it.

Fig. 4 is a perspective view of an attachment for one of the display members.

Fig. 5 is an end view of a modified form of display member.

Figs. 6 and 7 are end and plan views respectively of other forms of display members.

Fig. 8 is a fragmentary perspective view of the upper end of one of the shields.

The frame 10 may be of any suitable construction to permit the device to be handled and supported on the wall if desired.

A plurality of display devices 11 are provided one above the other in the frame and each preferably mounted on a shaft 12 which permits it to be slid back and forth horizontally.

Preferably one or more sides of each display device has painted or printed upon it a series of numbers, and preferably the numbers are arranged differently on the different display members.

To position the display members with the numbers in uniform column arrangement, I prefer to notch each shaft as at 13, and provide a spring member such as 14, adapted to snap into the notches or recesses in the shafts.

This spring member yieldingly holds the shafts at certain definite positions, but obviously the shafts may be readily shifted longitudinally and independently of each other.

To facilitate removal and replacement of the display members, the sides of the frame may be slotted as at 15, and removable cover plates such as 16 provided.

The shields such as 17, 17', and 17'' are preferably of thin material so as not to project much beyond the surface of the display members 11.

These shields are all supported by a bar 18 at the top, which is preferably horizontally slidable so as to move the shields across the faces of the display members.

The shields are preferably removably supported, as for instance by pins 19 in slots 20. Preferably there is a pin 19 to correspond with each figure on one of

the display members so that any column of figures may be covered up by a shield hung on the proper pin.

It is thus possible to display any set of figures desired by shifting the display members and the shields.

By having some of the surfaces of some of the display members blank, it is possible to more readily point out the desired problems.

110

Additional guards such as 21 may be provided to be slipped over one or more of the display members so as to cover up any that it may be desired to cover up. On the other hand, guards such as 21^a with special signs or characters may be provided to indicate the nature of the problem or call attention to various things in connection with the use of the apparatus.

- 10 Some means is preferably provided to hold the displayed members in their proper angular relation. In the construction shown, the shields hang across the faces of the display members and thus tend to hold them in position although they permit the display members to be rotated when it is desired to do so.

Obviously, the display members may be of different cross-sectional shapes, such as flat, as at 11^a in Fig. 5. They may also be in the nature of bands, such as 11^b, and shown in Figs. 6 and 7 guided around rods such as 22, and around the rotating roller or drum 23.

While this construction may be more expensive than that shown in Figs 1 and 2, it has the advantage of a greater variety of problems.

It will be obvious that some of the display members may be provided with letters, fractions, decimals, or other characters. It should also be understood that certain faces of the display members may be provided with sentences, words, or commands for carrying on consecutive drills.

35 In all of the foregoing, it will be seen that the effort has been to provide the teacher with material which may be set up under various circumstances and readily changed from time to time without requiring

ing the teacher to erase the problems from 40 the board and write down new problems.

I claim:

1. Educational apparatus comprising a frame, a plurality of horizontally adjustable slides carried by said frame one above 45 the other, each slide bearing on its face a row of digits, a horizontally adjustable carrier slide and a plurality of vertical shields mounted on said carrier slide and adjustable horizontally therewith, each of 50 said shields being wide enough to cover only a single column of digits.

2. Educational apparatus comprising a frame, a plurality of horizontally adjustable slides carried by said frame one above 55 the other, each slide bearing on its face a row of digits, a horizontally adjustable carrier slide and a plurality of vertical shields mounted on said carrier slide and adjustable horizontally therewith, each of 60 said shields being wide enough to cover only a single column of digits, one of said shields being movable with respect to the other shields whereby different widths of columns of figures may be disclosed.

65 3. Educational apparatus comprising a plurality of rows of changeable display members, arranged one above the other, and a plurality of vertical shields in front thereof, and means for simultaneously adjusting a plurality of said shields.

4. Educational apparatus comprising a plurality of horizontally disposed changeable display members, a horizontally adjustable support, means for securing vertical shields to said support at various positions thereon.

75 PALMER J. JONES.
